FASTENING FOR JEWELRY

Thomas S. Bennett, North Attleboro, Mass.

Application July 20, 1933, Serial No. 681,298

2 Claims. (Cl. 24—160)

This invention relates to a unit having a pin stem and catch therefor; and has for one of its objects the provision of a solderless unit construction comprising a pin stem, a joint therefor and catch, all of which may be handled together and attached to an ornament by solder, riveting or other means.

Another object of the invention is the provision of a simple catch and safety device therefor upon such a unit by the folding of a portion of the base of the unit to form the relatively stationary part upon which a rotary safety catch may be mounted.

Another object of the invention is the provision of a rotary safety catch in a simple and inexpensive manner which may be readily manipulated and assembled in position without the use of solder.

Another object of the invention is the provision of a safety catch which by reason of an increased and well balanced bearing, the rotary parts will not readily cramp but will be so supported that the same may be smoothly and readily rotated on its bearing.

Another object of the invention is the provision of a catch which may be of such construction as to entirely protect and guard the end of the pin stem that the same will not catch or abrade the garment upon which the device is mounted.

A further object of the invention is the provision of a safety catch which may be rotatably mounted at one end while the other end protrudes to receive and guard the pin stem point.

With these and other objects in view, the invention consists of certain novel features of construction, as will be more fully described, and particularly pointed out in the appended claims.

In the accompanying drawing:

Fig. 1 is a side elevation of my finding unit.

Fig. 2 is a central sectional view therethrough.

Fig. 3 is a section on the line 3—3 of Fig. 1.

Fig. 4 is a similar section showing another position of the rotary member with the same in open position.

Fig. 5 is a perspective view of the catch end of the bar upon which the parts are mounted.

Fig. 6 is a fragmental perspective view of one of the ears of the safety catch.

Fig. 7 is a perspective view of a modified form of construction showing the catch end of the unit.

Fig. 8 is a view similar to Fig. 7 with the pin omitted and the retaining sleeve as moved to open position.

Fig. 9 is a sectional view through the parts illustrated in Fig. 7.

Fig. 10 is a sectional view of a modified form showing a separate catch secured in position without solder.

Fig. 11 is a section on line 11—11 of Fig. 10.

Fig. 12 is a section on line 12—12 of Fig. 11.

It is frequently desirable to provide a unit which may be attached to an ornament for the formation of a bar pin or the like, without the necessity of assembling separate parts upon such ornament and the aligning of these parts that they may properly function, and to provide such a finding unit without the use of solder, I have used a bar as a base having a pin stem joint mounted at one end and a catch at the other end for receiving the pin stem. This catch is so arranged as to cooperate with the integral parts of the bar in its operation. I have also arranged the catch in such a manner that the pin stem point is entirely protected and thus will not abrade any fabric or parts upon which it is mounted; and in order that these results may be accomplished in a simple construction I may turn the end of the bar or base in such a manner as to form a mounting for the safety catch and in some instances to itself serve as a part of the catch for retaining the pin stem, and in order that the safety catch may have a smooth action and one which will not cramp by pressure at one side, I have provided a bearing on either side of the stationary part to better distribute and support pressures which may tend to move the same; and the following is a detailed description of the present embodiment of this invention illustrating the preferred means by which these advantageous results may be accomplished.

With reference to the drawing, 15 designates the base or bar of a finding unit, which is pierced as at 16 to provide for attaching the same to a suitable ornament. At one end of this bar a pair of ears 17 are secured by means of fingers 18 extending through the bar and riveted as at 19. These fingers are integral with the web 20 extending between the ears 17. Each of these ears has a portion forced inwardly as at 21 to provide pivot trunnions to extend into an eye 22 of the pin stem 23 which is hingedly supported in this manner and limited in its movement towards the bar by a suitable stop 24 while it is also limited in its opening movement by a similar stop 25 upon the opposite sides of the ears.

The opposite end portion 26 of the bar 15 is folded at generally right angles to the bar and is shaped to provide a hook 27 having an entrance opening 28 and a generally circular recess 29 in which the pointed end 30 of the pin

stem 23 may be lodged to be maintained under pressure by reason of the resilience in the pin stem 23 and the flexure thereof over the stop 24.

The receiving opening 29 of this hook forms a bearing for the safety catch, which consists of ears 31 joined together by a bridge portion 32 with each ear having an inwardly extending portion 33 fitting within the opening 29 and having a bearing therein by which these ears are rotatably supported for movement through an arc of substantially 270°. The arc is limited by reason of the bridge and handle portion 32 engaging the base of the hook at 34 on one side or the base at 35 on the other side thereof, as illustrated respectively, in Figs. 3 and 4. As each of the ears has this portion extending into the opening a substantial and well balanced bearing is formed which will not become jammed by pressure on one side only.

These ears are slotted as at 36 so that when the bridge 32 is in the position illustrated in Fig. 4 there will be an opening into the center of the hook, while when this bridge is rotated to the position illustrated in Fig. 5, this opening will be closed both by reason of the ear, the bearing and the bridge portion so that the free end portion of the pin stem cannot escape therefrom.

These ears together with the right angularly extending portion 26 of the bar are of sufficient width to completely embrace the pointed portion of the pin stem and prevent the same from catching on or abrading any of the fabric with which the same comes in contact.

In some instances, I may desire to use a different construction such as that illustrated in Figs. 7, 8 and 9. In this case, the bent or right angular portion of the bar 15 is designated 37 and is provided with a cylindrical opening 38 to receive a sleeve portion 39 of the safety catch which is enlarged as at 40 to form an abutment and handle by which the same may be manipulated. This sleeve 39, which protrudes a substantial extent from its bearing in the opening 38, is cut away as at 41 so as to receive the pointed portion of the pin stem therein after which this sleeve may be rotated to cover this pointed portion of the pin stem as illustrated in

Figs. 7 and 9, to prevent the outward pressure, as explained above, from releasing this pin stem from position. Also in order that the pin stem may not be flexed to permit it to escape from the retaining sleeve 39, I provide an abutment 42 which may be cut and raised from the stock of the bar 15 with which the pin stem will engage to prevent it from escaping from the sleeve when in the position shown in Figs. 7 and 9.

In Figs. 10, 11 and 12 I have illustrated a catch 45 which has a square shank 46 threaded on its corners enabling it to be threaded into an opening 47 in the bar to be retained in place and in aligned position by forcing the stock 48 of the bar against the flat portion of the shank and thus mounted upon the bar quickly and without the use of solder.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A safety catch comprising a keeper for the pin having a central opening, a locking member comprising a pair of ears on opposite sides of said keeper, each ear provided with a tapered bearing trunnion extending into said opening for rotatably supporting said member on said keeper, and means connecting said ears together for movement in unison and serving as a handle for rotating said member.

2. A safety catch comprising a hook-shaped keeper for the pin having a central opening, a locking member comprising a pair of ears on opposite sides of said keeper, each ear provided with a tapered bearing trunnion extending into said opening for rotatably supporting said member on said keeper, said member being slotted to register with the opening to the hook in one position, and means connecting said ears together to move in unison and serving as a handle for rotating said member to move the slot out of registry with the opening to said hook.

THOMAS S. BENNETT.
